ESCUTCHEON PLATE FOR A STOVE OR RANGE

Jack B. Stuman, Rockford, Ill., assignor to Geo.
D. Roper Corporation, Rockford, Ill., a corpo-
ration of Illinois

Application January 15, 1953, Serial No. 23,158

Term of patent 7 years

(Cl. D81—25)

To all whom it may concern:

Be it known that I, Jack B. Stuman, a citizen of the United States, residing at Rockford, in the county of Winnebago and State of Illinois, have invented a new, original, and ornamental Design for an Escutcheon Plate for a Stove or Range, of which the following is a specification, reference being had to the accompanying drawing forming part thereof.

In the drawing:

Figure 1 is a top plan view of an escutcheon plate for a stove or range embodying my new design;

Figure 2 is a front elevational view thereof;

Figure 3 is a bottom plan thereof;

Figure 4 is an end view thereof, taken from the left end of the plate; and

Figure 5 is a right end view of the escutcheon plate.

The characteristic features of the design reside in the portions shown in full lines.

I claim:

The ornamental design for an escutcheon plate for a stove or range, substantially as shown and described.

JACK B. STUMAN.
